GEARING

Reginald Bishop, Golders Green, London,
EnglandApplication April 18, 1934, Serial No. 721,200
In Great Britain July 10, 1933

6 Claims. (Cl. 74—458)

This invention relates to gearing that is particularly, though not exclusively, applicable to the steering of mechanically propelled road vehicles, which gearing is of the kind (hereinafter referred to as the kind specified) that comprises a cam which is engaged by a follower mounted on a rocker-arm that is angularly movable parallel to the side of the cam, the said rocker-arm being mounted on a rocker-shaft.

10. In gearing of the kind specified which I have previously invented the cam is in the form of a worm thread of constant diameter but not a true helix, the follower is a pin or roller, the rocker-arm is movable in a plane parallel to the longitudinal axis of the cam, and the axes of the rocker-arm and of the follower are at right angles. Other gearing of the kind specified also invented by me is generally similar to that just described except that the follower is in the form of an elongated shoe.
15. It is an object of the invention to cause the follower to rock in a predetermined manner on its pivot during rotation of the cam and thereby to avoid or minimize binding action between said cam and follower.

20. It is an object of the invention to cause the follower to rock in a predetermined manner on its pivot during rotation of the cam and thereby to avoid or minimize binding action between said cam and follower.

25. One feature of the invention is gearing of the kind specified having means to move the follower about its axis by predetermined amounts in accordance with the movement of the follower-carrying arm about the axis of the rocker-shaft.

30. The invention will become more fully apparent from the following description, in conjunction with the accompanying diagrammatic drawings, of one construction of gearing according to the invention.

35. In the drawings,

Fig. 1 is a view in elevation, partly in section, of gearing according to the invention;

40. Fig. 2 is a view in elevation, partly in section, at right angles to Fig. 1;

45. Fig. 3 is a diagram showing an alternative method of producing the desired movement;

Figs. 4 and 5 are diagrams indicating an alternative form of follower; and

50. Fig. 6 is a view similar to Fig. 2 of an alternative construction.

Referring to Figs. 1 and 2 the worm or cam 11 of the gearing is of constant diameter and constant pitch. A follower 13 is in the form of a single elongated shoe which fits into the thread of the worm. This shoe 13 is, in this particular case, integral with a pivot-pin 15 of large diameter which is mounted for oscillation in a bearing 17 in the free end 19 of a rocker-arm 21 which is fixed upon a rocker-shaft 23, the arrangement

being such that the axis of the pivot-pin 15 is parallel with the axis of the rocker-shaft 23. The pivot-pin 15 is extended so as to pass right through the rocker-arm 21 and on its rear end it is provided with a crank-pin 25. This crank-pin 25 has pivoted on it a block 27 which is located and guided in an arcuate cam-slot 29 which is formed in a stationary member 31 which in this particular construction forms the back wall of the gear casing 33. The arcuate cam-slot 29 is of the same mean radius as the effective radius of the rocker-arm 21 and is struck about a centre 35 (Fig. 2) which is offset from the axis 24 of the rocker-shaft 23 by the same amount that the axis of the crank-pin 25 is offset from the axis 10 of the pivot-pin 15. The arrangement is such that as the cam 11 rocks the rocker-arm 21, the block 27 will be driven along the cam-slot 29 and will lift or lower the crank-pin 25 to rock the pivot pin 15, with the result that the follower 13 will be rocked in such a manner that in all positions the longitudinal middle line of the follower will (in this particular construction) remain parallel to its original position.

15. The block 27 may be in the form of a ring (or the block may be omitted and the pin be large enough to take its place) encircling the crank pin 25; this would give line contact with the cam slot 29. It is preferred, however, to form the block 27 as an elongated arcuate slider (see Fig. 2), as this will give extended surface contact with the cam-slot 29 and so will induce more easy operation than is possible with line contact.

20. A somewhat similar result might be obtained by the use (instead of the crank-pin and cam-slot) of a radius arm 41, Fig. 3, on the pivot-pin 15, a pin 42 on the casing eccentric to the axis of the rocker-shaft 23 by the same amount as the effective length of the radius arm 41, and a link 43 connecting the pin 42 and the arm 41; the radius arm might if desired be made adjustable in length. Or by a toothed quadrant on the pivot-pin, a fixed toothed quadrant and the two quadrants being of the same pitch diameter and meshing with an idler pinion on the rocker-arm. 25. Or, the quadrants might be replaced by drums and the idler pinion by a crossed belt wrapping round the drums.

30. It may be desired that the longitudinal middle line of the follower should not always be parallel with its original position, but should be displaced from such position by predetermined amounts during its travel, the displacement being, for instance, proportional to the displacement of the rocker-arm from its mid-position. This result 35

might be attained, for example, by altering the shape of the cam-slot 29.

The follower 13 has been described as a single elongated shoe; the follower might be a multiple shoe, for example a double shoe 13a, 13b (Figs. 4 and 5) with a groove between the parts so that the land of the cam worm would fit into the groove of the follower. In this case the rocker-arm 21 might be extended as at 21a into adjacent 10 grooves of the cam worm 11 so as to embrace approximately the whole depth of the shoe at about its middle; thus the side thrust and consequent canting action on the shoe would be taken directly by that portion of the rocker-arm 15 opposite the portion of the shoe receiving such thrust.

In a further alternative (see Fig. 6) the follower instead of being supported in the rocker-arm 21 is supported in and is free to rotate in 20 a block 27 which travels along an arcuate slot 51 in a member 53 fixed to the casing; the pivot-pin 15 of the follower passes through this block 27 and through the fixed member 53, and has fixed to it a crank arm 55 having a crank-pin 25 57 which is pivoted in the upper end of the rocker-arm 21.

What I claim is:—

1. Gearing comprising a cam, an elongated follower operatively engaging said cam, a rocker-arm upon which said follower is pivotally mounted, a rocker-shaft carrying the said arm in 30 such manner that the latter is angularly movable parallel to the side of the cam, and control means acting between a fixed part of the gearing and said follower and operative for imparting positively to the latter a predetermined pivotal movement dependent upon the rocking movement of the rocker-arm.

2. Gearing comprising a worm-like cam, a 40 rocker-shaft, a rocker-arm carried by said rocker-shaft, a pivot-pin mounted for oscillation in relation to the rocker-arm, an elongated follower carried by the pivot-pin and operatively engaging with the cam, crank means connected 45 to the pivot-pin for oscillation therewith, and an operative connection between said crank means and a fixed part of the gearing, the said connection being adapted for imparting a posi-

tive oscillatory movement through the crank means to the pivot-pin and follower as the rocker-arm is rocked.

3. Gearing comprising a fixed body, a worm-like cam rotatable in relation to said body, a 5 rocker-shaft, a rocker-arm carried by said rocker-shaft, a pivot-pin oscillatable in the rocker-arm, an elongated follower carried by the pivot-pin and engaging with the cam, a crank-pin also carried by the pivot-pin, an arcuate cam-slot 10 formed in the fixed body and having the crank pin guided in it, the said cam-slot having a mean radius equal to the effective radius of the rocker-arm and being struck about a centre that is offset from the axis of the rocker-shaft by the 15 same amount that the crank-pin is offset from the axis of the pivot-pin.

4. Gearing comprising a cam with a worm-like land, a follower having an elongated groove into which fits the land of the cam, a rocker-arm 20 upon which said follower is pivotally mounted; a rocker-shaft carrying the said arm in such manner that the latter is angularly movable parallel to the side of the cam, and control means acting 25 between a fixed part of the gearing and said follower and operative for imparting positively to the latter a predetermined pivotal movement dependent upon the rocking movement of the rocker-arm.

5. Gearing according to claim 4, comprising 30 also arcuate cheeks embracing the follower and extending from the rocker-arm into the grooves formed between the part of the cam-land engaged by the follower-groove and the parts of said land on each side thereof.

6. Gearing comprising a fixed body, an actuating element in the form of a worm-like cam rotatable in said fixed body, an elongated follower engaging said cam, a rocker-arm, a pivotal mounting on said rocker-arm for said follower, 40 an actuated element in the form of a rocker-shaft carrying said rocker-arm, and an operative connection between the follower and a part of the fixed body whereby a positive oscillatory movement is imparted to said follower as it 45 traverses the worm-like cam.

REGINALD BISHOP.
